UNITED STATES PATENT OFFICE.

CLARENCE E. CARR, OF ANDOVER, NEW HAMPSHIRE.

HAME.

SPECIFICATION forming part of Letters Patent No. 431,556, dated July 8, 1890.

Application filed January 21, 1889. Serial No. 297,045. (No model.)

To all whom it may concern:

Be it known that I, CLARENCE E. CARR, a citizen of the United States, residing at Andover, in the county of Merrimac and State of New Hampshire, have invented certain new and useful Improvements in Hames, of which the following, taken in connection with the accompanying drawings, is a specification.

My invention relates more particularly to improvements in the attachments on the upper parts of hames used for attaching the upper hame-strap and in the form, construction, and attachment of the terrets or rings through which the reins lead. The object thereof is to allow the loop through which the hame-strap passes and the rein-terret to be readily adjusted at different heights on the hame and to allow them to be easily replaced in case they are broken or worn out, and to hold the strap-loop securely in place, also to provide convenient strap-holes at different heights for the upper hame-strap in case through accident or for any cause it is not possible or desirable to use the loop.

In the accompanying drawings, Figure 1 is a side elevation of the upper portion of a hame with my improved hame-strap and rein-terret attachments. Fig. 2 is the rein-terret detached. Fig. 3 is a side elevation of one of the starts. Fig. 4 is a view of another form of my hame-strap and rein-terret attachment. Fig. 5 shows another form of rein-terret and method of attaching it. Fig. 6 is another form similar to that shown in Fig. 4, in which a part of the starts D are formed without eyes and a part with eyes.

Like letters of reference designate like parts in each of the figures.

A represents the upper portion of a hame; B, the rein-terret; C, a loop, preferably of metal, for attaching the upper strap.

D D D D are metallic starts with eyes or holes in the outer end for the rod, pin, or split key E, which passes through the starts as well as through holes or eyes in the ends of the terret B. The rod E may be fastened in place by a head or eye on one end and being split and opened at the other end, as shown in Fig. 1 or by a nut or other suitable fastening on one end or it may have a thread cut on it to screw into a thread cut in one or more of the starts D or it may be secured in any

other convenient manner. The rod E may be formed so as to make the terret B, Fig. 5, and may be removed by springing the end from 55 the start D. It may be engaged with the starts so as to bring the terret B between any two of the starts.

The starts D may be secured in place by driving them into the hame-wood, or they may 60 have a thread cut on them and be screwed into the hame wood or iron or they may pass entirely through the hame and be held by riveting or they may be secured to the hame by any other suitable means. Any convenient number of starts may be used, and it is not necessary that the pin E should pass through all of them. The others may meet the pin in any suitable manner so as to form the strap-holes h, substantially as shown in 70 Fig. 6.

The terret B may be wrought with the ends turned on themselves to form the holes for the pin E, or it may be cast.

Any shaped terret having an eye in it for 75 the passage of the rod E may be used; but I prefer a terret of the shape shown in Figs. 2 and 5, for with this shape, which I believe to be new, a longer opening may be had for the passing of the reins and buckles than in the 80 terrets in common use without increasing the general size of the ring.

Adjustable loops similar to the one shown in the drawings are in common use; but they usually rest in corrugations or between pins 85 on the outer or back side of the hame with nothing to hold them in place until the strap is passed through the inner end of the loop, filling the spaces between the loop and the inner edge of the hame, and heretofore it has 90 only been feasible to use them with hames whose inner edges at the upper end of the hame have a flat surface; and when the strap is removed from the hames commonly in use the loop is liable to fall from its place or from 95 the hame and be lost. With my improvement the loose loop C can be advantageously used on all hames, whatever be the contour of the surfaces on the inner sides, and it will not fall from place when the strap is removed. 100 Single parts of the attachment that may be broken or lost can be easily and cheaply replaced, and both loop and terret can be adjusted at any desired height. When applied

to hames not having a flat inner surface, and which heretofore have had strap-holes cut into the hame-wood, the necessity for such strap-holes with the consequent weakening of the 5 hame and liability of breaking is avoided.

If desired, the whole attachment can be constructed, as shown in Fig. 4 or Fig. 6, by casting the starts D on a base F or by fastening 10 the whole to the hame by rivets or other appropriate means. In general adaptability, convenience, and durability, my construction is greatly superior to anything heretofore used for the purpose known to me.

15 The various parts of my devices are simple, strong, and cheaply made, while, should any part become broken, such part can be quickly and easily replaced by any one with very limited mechanical skill. The ready adjustability, as described, also enables the hames to which my invention is attached to most perfectly fit the different styles and sizes of collars. These features are of great importance and utility in practical use.

20 25 Having thus described my invention, what I claim as new, and desire to secure by Letters Patent, is—

1. The combination of the hame A, loop C, and strap or loop holes h, formed by starts D 30 and pin E, all suitably arranged and adapted to operate substantially as and for the purposes set forth.

2. In a hame, the combination of a rein-terret with starts suitably secured to the hame,

and a pin adapted to engage and to hold the 35 said rein-terret, substantially as herein shown and described.

3. In a hame, an adjustable rein-terret combined with suitable starts secured to the hame, and a removable pin adapted to secure said 40 rein-terret between said starts, substantially as and for the purposes set forth.

4. In a hame, the combination of strap-holes formed by suitable starts secured one above another to said hame and a pin formed 45 at one end to make a rein-terret and to be removably secured to the outer ends of the said starts, with a strap-loop adapted for securing the hames above the collar, substantially as and for the purposes set forth. 50

5. In a hame, the combination of starts suitably secured to the hame one above another, a removable pin adapted to engage with one or more of said starts, and an adjustable open-loop rein-terret, all substantially as and for 55 the purposes set forth.

6. The combination of the hame A, the herein-described open loop, adjustable rein-terret B, the starts D, and the pin E, substantially as and for the purposes set forth. 60

In testimony whereof I have signed my name to this specification in the presence of two subscribing witnesses.

CLARENCE E. CARR.
